Inventor

Chas. Spencer

UNITED STATES PATENT OFFICE.

CHARLES F. SPENCER, OF ROCHESTER, NEW YORK.

LAMP.

SPECIFICATION forming part of Letters Patent No. 231,688, dated August 31, 1880.

Application filed January 15, 1880.

To all whom it may concern:

Be it known that I, CHARLES F. SPENCER, of the city of Rochester, county of Monroe, and State of New York, have invented a certain 5 new and useful Improvement in Lamps; and I do hereby declare that the following is a full, clear, and exact description of the same, reference being had to the accompanying drawings, in which—

10 Figure 1 is an elevation of a lamp supported by my improved holder and forming a bracket-lamp. Fig. 2 is a longitudinal horizontal section of the holder.

15 My improvement relates to holders for lamps, by the use of which an ordinary stand-lamp may be used as a bracket-lamp.

The invention consists of the combination, with the hollow standard, of adjustable jaws 20 for clamping the standard of the lamp and a screw for operating the jaws.

In the drawings, A represents the base of the holder, which may be round, square, or of any other suitable form. On the back side of this base is cross-wire or other device, a, which 25 catches on a hook in the wall, as shown in Fig. 1.

B is a projecting standard attached to the base, made hollow, and C C are the jaws or forks by which the lamp is supported. These 30 jaws are made as shown in Fig. 2, in which case the two jaws pass through an opening in the end of the hollow standard, and have shanks b b, which extend inward, and are attached to a block, c. This block has a female 35 screw, through which passes a male screw, D, which passes back through the base A, and

has on the back side a shoulder, d, and a thumb-piece, f, by which it is turned. As the screw D is turned forward or back the jaws C C will be correspondingly thrown in or out 40 through the socket in the end of the standard. The ends of the jaws which rest in said socket are inclined, as shown at g g, and the shanks are made of spring metal, so that as the jaws are drawn in by the screw they will be clamped 45 together to bind upon the standard of the lamp, and as the jaws are forced out they expand by their own elasticity and release the lamp.

By the use of the holder above described an 50 ordinary stand-lamp may be at once converted into a bracket-lamp, thereby saving the expense of two separate lamps for the purpose or a lamp which is specially constructed for that purpose.

Having thus described my invention, what I claim as new, and desire to secure by Letters Patent, is—

In a lamp-holder, the combination, with the hollow standard B, of the adjustable jaws C C, passing through a hole or socket in the end of the standard, and connected with the screw D, by which said jaws are operated, as herein shown and described.

In witness whereof I have hereunto signed 65 my name in the presence of two subscribing witnesses.

CHAS. F. SPENCER.
